DIAVISION

Aloysius J. Cawley, Pittston, Pa.

Original application March 19, 1931, Serial No. 523,791. Divided and this application April 8, 1937, Serial No. 135,718

2 Claims. (Cl. 250—1)

The invention has for its object in general, the perception of objects by means of electric waves which are longer than the visible light waves, but which are much shorter than those used in present day broadcasting. Since such electromagnetic waves are subject to all of the laws of reflection, refraction and polarization as are ordinary light waves, a beam of those waves is directed upon a body possessing the power of refracting them. An invisible image is formed of those reflected waves, and this invisible image is converted into a visible image by means of the apparatus described in this application.

This application is a division of my application Serial No. 523,791, filed March 19, 1931, for Fog and mist penetrating device, Patent No. 2,155,471, April 25, 1939.

The waves may be generated by any ordinary means, such as by vacuum tubes, Hertzian resonators, induction coils, Hertzian vibrators, by an antenna or a plurality of antennae connected to suitable sources of high frequency alternating current. One of the main objects of the invention is the formation of images by means of electromagnetic waves, which images are converted into visual images, thus making it possible to perceive objects through mists, buildings, dry earth, and in fact through nonconductors in general.

The accompanying drawing forming a part of this specification are to be referred to, in which like reference characters have similar meanings in all of the views, and in which,

Figure 1 is an elevational cross sectional view of an apparatus forming invisible electromagnetic wave images and rendering those images visible and employing a rotating element.

Figure 2 is a view of a disk, which may be used in conjunction with the apparatus illustrated in Figure 1 by substituting it for the rotating element illustrated therein.

Figure 3 is a view of an apparatus for forming visible images from electromagnetic wave invisible images after the method illustrated in Figure 2.

Figure 4 is a side view of Figure 3, showing the means carried on the surface of the cylinder for scanning the visible and invisible images.

Figure 1 illustrates a device employing a smaller number of rotating elements to produce the images. The apparatus consists of a casing D made of metal or covered with metal foil, for the purpose of eliminating stray electromagnetic waves from the camera-like structure. A part of the casing is telescopically arranged as C. Thus an adjustable means is provided for focus-

sing the lens I. The electromagnetic waves reflected from the objects are received by lens I and focussed into an invisible image. In the plane of this image, there is a rotating disk E which turns upon shaft J, and connected to any suitable source of power by means of pulley I2. This disk E is provided with a cylindrical peripheral portion which bears two collector rings h and i. On the left face of the disk there is a spirally arranged series of coils or antennae K, which traverse, or scan the invisible image, and have thus generated in them alternating currents of varying intensity. One terminal of each of the coils is connected to collector ring H, while the other terminal of each coil is connected to a specific commutator segment of commutator u. Brush O plays on a commutator segment to which a coil which happens to be traversing or scanning the image field is connected. The square of Figures 5 and 7 represents a detecting and amplifying circuit, which may be tuned to any wave length desired. The current generated in the coil K passes through wire to collector ring h, thence through brush q, which is in contact with collector ring h. It then passes through the wire connected to brush q to the detecting, amplifying and tuning circuit 10, and returns to brush o commutator u and back to coil K. Therefore, the current generated in a coil or antenna K is amplified by element 10 and transmitted by wires to brushes p and v. On the right hand side of the disk a series of spirally arranged glow lamps, such as neon lamps l is arranged. One terminal of each lamp l is connected to collector ring i and the other terminal of each lamp l is connected to a specific commutator segment. An important fact is that the two spirals, one of coils and one of lamps, although concentrically arranged, have their corresponding points displaced relative to each other by an angle of 180 degrees. The purpose of this is to produce a right side up luminous image opposite the window H, at the lower portion of the right side of the disk E. It will be seen that the current which has been amplified, will be delivered by means of the commutator u' and brushes p, v to that lamp which is traversing the visual image field opposite the window H through which it may be viewed. The manner of the reversal of the luminous image relative to the invisible image will be better understood by reference to Figure 2, which illustrates two spirals of different sizes, whereas the spirals of coils and lamps of Figure 1 are of equal size. Nevertheless, the spirals containing lenses f and r serve to demonstrate that

the beginning of one spiral is in the upper portion of the disk E', while the beginning of the other spiral is in the lower portion, or displaced by 180 degrees.

5 Figure 2 illustrates a disk E' which may be substituted for the rotating element in Figure 1. This disk is composed of metal and has two spirals of holes or lenses f and r. A photoelectric cell or coil or antennae is placed between the disk 10 and observer at I, assuming that the disk has been substituted for disk E in Figure 1. The lenses f may be of paraffin, etc. The invisible image is produced at I, but the holes or lenses limit the area of it that is scanned at any instant. The 15 photoelectric cell or antenna is connected to 10, where the current is amplified and then delivered by suitable wires to the glow lamp at H. This glow lamp has its intensity varied in synchronism with the variations produced in the antenna at I, and glass lens r scans the lamp face in reverse order to that of the scanning by the paraffin lenses f at I. Thus a luminous image is produced at H. The arrows indicate that the disk E' rotates counterclockwise and that the 20 upper image is scanned from right to left and from bottom to top, while the lower image is scanned from left to right and from top to bottom. Thus the inverted invisible image is converted into a right side up visible image, which 25 is viewed at H.

Figure 3 is an illustration of a device similar to that of Figure 2, but differs in that a cylinder is used having two helices of scanning apertures or lenses on its cylindrical surface. Lens I forms 30 an invisible image through the aperture t upon photoelectric cell s or wire or coil of wire or antenna, as desired. C is the metallic casing which excludes the extraneous electromagnetic waves. The cylinder rotates on shaft J similar to disk 35 E' of Figure 2. The two juxtaposed helices on the cylindrical surface are relatively displaced by an angle of 180 degrees, as described above. The cylindrical surface of this cylinder at least should be made of metal. As the cylinder rotates, the invisible image is scanned as described 40 in connection with the above figures. The result is that the photocell s has varying amounts of electric current generated in it; or the antennae has varying degrees of electric current 45 generated in it. (A chopper may be included with the photocell in the well known manner.) The current is delivered to the amplifier 10, and the amplified current is delivered to neon or other glow lamp I. A separate helix scans the 50

lamp area producing a visible image. This may be viewed through the aperture or frame in the partition w. Due to 180 degrees displacement in the two helices, a right side up image is produced at the neon lamp.

Figure 4 is a view of the cylindrical surface of the cylinder E', and shows the two juxtaposed helices consisting of holes or lenses r and f. The dotted arrow at image area I shows that the helix scans from top to bottom and right to left. The 10 full line arrow at H shows that the helix made up of holes f scans the image area at H from bottom up and left to right. However, as this cylinder is supposed to be placed in a horizontal position, the scanning in the latter aperture 15 will be from top to bottom and left to right, or conventional scanning.

In the rotating modifications illustrated in Figures 1 and 4, it is to be understood, of course, that the elements rotate with sufficient speed 20 as to produce the effect of a continuous image by means of the persistence of vision of the eye.

Having described my invention, I claim as new and desire to secure by Letters Patent:

1. In combination: means for forming an invisible image of electromagnetic waves, a series of spirally arranged rotating coils or antennae placed substantially in the focal plane of said invisible image, said coils being so arranged as to consecutively pass through the field of said image, means for consecutively connecting said coil to a source of amplification, means for connecting the amplified current from said source consecutively to each of a series of spirally arranged rotating glow lamps, whereby said lamps 35 traverse or scan a visible image field to produce a varying diffuse glow in said field, constituting a corresponding visible image.

2. In combination: means for forming an invisible electromagnetic wave image, a rotating 40 member in the field of said image, a plurality of wave-to-current converting means spirally arranged on one side of said rotating member, means for connecting consecutively each of said wave-to-current converting means to a source 45 of amplification, means for consecutively supplying said amplified current to each of a plurality of current-to-light converting means spirally arranged on the opposite side of said rotating member during the time said current-to-light 50 converting means traverses the field of a visible image, thus producing a visible image therein.

ALOYSIUS J. CAWLEY.
